FIG. 5.

UNITED STATES PATENT OFFICE.

WILLIAM HUMPHRY PERRIN, OF NEW LISKEARD, ONTARIO, CANADA.

SHOCKER.

1,218,694.

Specification of Letters Patent. Patented Mar. 13, 1917.

Application filed May 11, 1915. Serial No. 27,420.

To all whom it may concern:

Be it known that I, WILLIAM HUMPHRY PERRIN, of the town of New Liskeard, in the district of Nipissing, in the Province of Ontario, Canada, have invented certain new and useful Improvements in Shockers, of which the following is the specification.

My invention relates to improvements in shockers, of that class which gathers the 10 sheaves into the form of a round shock and deposits the shock so formed in an upright position on the ground and the object of the present invention is to construct a simple, light, cheap and durable attachment 15 for a harvester binder, which will either gather the sheaves into a complete shock and deposit the shock or will gather and deposit any number of sheaves forming an incomplete shock when so desired.

20 My invention is illustrated in the accompanying drawings in which—

Figure 1, is a perspective view of my device and a portion of a binder deck and delivery mechanism of the binder.

25 Fig. 2, is an enlarged perspective detail of the main revolving member of the shocker.

Fig. 3, is a cross section through Fig. 2.

20 Fig. 4, is a plan section on line $x-y$ Fig. 3.

Fig. 5, is a plan section through the sheaf receiving pockets.

Fig. 6, is an enlarged perspective detail of the pivotal arm supporting members.

35 Fig. 7, is a cross sectional view on line $x'-y'$ Fig. 3.

Fig. 8, is a perspective detail of the ratchet member for manually releasing the sheaves.

40 Fig. 9, is an elevation of one of the cams operating the delivery arm of the binder showing a knotter shaft bearing and knotter shaft in section.

Fig. 10, is a perspective detail of one of the gathering forks.

In the drawings like characters of reference indicate corresponding parts in each figure.

1 indicates a portion of an ordinary 50 binder deck, 2 the compressor arm, 3 the knotter shaft and 4 the knotter shaft bearing. 5 and 6 indicate the delivery arms of the binder pivotally supported on arms 7 carried by a revolving member 8 secured to the knotter shaft. 10 and 11 indicate cams mounted in a stationary position on the bear-

ing 4. The delivery arms 5 and 6 are provided with tail pieces 5^x and 6^x on which are journaled cam rollers 12 and 13 co-acting with the cams 10 and 11.

On referring to Fig. 9 of the drawings it will be seen that the cam 11 gradually increases in radius from the top to bottom for a purpose which will hereinafter appear.

14 and 15 are standard bars forming part 65 of the main frame of the shocker and carrying a bracket 15^x. 16 indicates a tubular bearing secured to the bracket 15^x by a clip bolt 16^x. 17 indicates a clip bolt extending over the tubular bearing 16 intermediate of 70 its length and extending through a cross piece 17^x. The cross piece 17^x is supported by suitable braces 19 and 20 connected to the standard bars 14 and 15. 21 indicates a circular plate provided with diametrically opposite radial extensions 22 and 23. The plate 21 is connected to the tubular bearing 16 by clip bolts 24 and 25. 26 indicates a bearing boss carried by the extension 22. 27 indicates a shaft journaled in the tubular 80 bearing 16. 28 indicates a bevel pinion secured to the inner end of the shaft 27. 29 indicates a vertical shaft journaled at its upper end in a bearing 30 formed integral with the bracket 15^x and at its lower end in 85 a bearing 30^x formed integral with the bearing sleeve 4. 31 indicates a bevel gear secured to the knotter shaft 3 and meshing with the bevel gear 32 secured to the lower end of the vertical shaft 29. 33 indicates a 90 bevel pinion secured to the upper end of the shaft 29 in mesh with the bevel pinion 28. 34 indicates a bevel pinion secured to the opposite end of the shaft 27. 35 indicates a stationary vertical axle suitably secured at 95 its upper end in the center of the plate 21. 36 indicates a revoluble member provided with an annular upwardly extending flange 36^x in the upper edge of which is formed an annular gear 37.

100 It will be noticed on referring to Fig. 3, that the plate 21 is provided with a depending central boss 21^x through which the axle 35 extends, the upper face of the plate being provided with a recessed portion 38 for a 105 purpose which will hereinafter appear.

39 indicates a normally stationary cupped tripping member provided with a central orifice 39^x through which the axle 35 extends. The base of the cup fits between the 110 boss 21^x and the central portion or hub of the revoluble member 36. The upwardly

extending flange portion of the cup fits against the lower face of the plate 21 and is provided with an annular outwardly extending flange portion 40 provided with 5 ratchet teeth 41. The revoluble member 36 is supported in position upon the axle 35 by a cross pin 42. 43 indicates my sheaf receiver. The sheaf receiver 43 is formed by a plurality of canvas strips 44, 45 and 46. 10 When constructing the receiver these strips are laid one upon the other and stitched together by a line of stitching extending vertically down the center of the strips. The outer strips 45 and 46 are turned outwardly 15 at an angle, each of the strips being provided with hems 47 in which are inserted reinforcing wires 48, see Fig. 5, holding the strips in place to form the pockets 49, 50, 51, 52, 53 and 54. 55 indicates a sleeve freely 20 mounted upon the axle 35 and provided with an annular outwardly extending flange 56 to which the inwardly extending upper ends of the wires 48 are suitably secured. 57 indicates 25 an inverted U-shaped bar secured at its lower end in the flange 56 and extending at its upper or looped end over a pair of spokes of the revoluble member 36 as indicated in Fig. 2 of the drawings. By this means the receiver 43 is carried so as to revolve with the member 36. 58 indicates a 30 collar loosely mounted upon the axle 35 and provided with radial arms 58^x. 59 indicates lugs extending from the revoluble member 36 and arranged in pairs. 35 60 indicates an arm supporting member. The member 60 comprises a central hub portion 61 having a central orifice 62. 63 indicates an arm extending from the portion 61 provided with a laterally extending lug 64 having an orifice 64^x and a downwardly 40 extending lug 65 having an orifice 65^x. 66 indicates a tail piece extending from the portion 61 and provided with an inwardly extending projection 67. The tail piece 66 normally extends above the lugs 59 as indicated 45 particularly by dotted lines in Fig. 3 of the drawings. When the arm supporting member 60 is in position shown by dotted lines in Fig. 3 the projection 67 bears against the lower face of the geared portion 50 of the revoluble member 36. 68, 68, indicate a series of arms, each arm comprising an inverted L-shaped portion, the short arm 68^x of the L extending inwardly and radially 55 of the revoluble member 36 and resting upon the flange portion 64 of the member 60. The inner end of the short arm 68^x is provided with a hooked portion 69 which extends through the orifices of the lugs 59 and through the orifice 62 of the hub 61 60 and forming the pivot pin of the member 60. 70 indicates an L-shaped bolt extending over the arm 68^x against the vertical flange 70^x of the member 60, the vertical portion 65 of the bolt being provided with a threaded

end extending through the orifice 64^x being secured therein by a nut 71.

The lower end of each arm 68 is provided with a forked end 72. 73, 73, indicate the gathering forks. The upper end or shank 70 of each gathering fork 73 is provided with a double cross arm 74, the outer end 74^x of which is pivoted into the forked end of the arm 68. It will be noticed particularly on referring to Fig. 10 of the drawings that 75 the shank of the fork joins the arm 74 intermediately of its length, instead of at the inner end. By this means when the fork receives the load it does not exert as great a leverage on the arm 68 tending to carry 80 the arm outward away from sheaf tending to free the sheaf. By constructing the fork as described the sheaf is held positively until it arrives at the tripping point to be discharged. 75, 75, indicate levers. A lever 75 85 is pivoted intermediately of its length to each of the lug portions 65 by bolts 76. 77 indicates a link connecting the inner end of each lever to each of the arms 58^x of the sleeve 58. 78 indicates a bar pivoted at its upper 90 end to the outer end of each lever 75 and provided at its lower end with an out-turned portion 79. 80 indicates a link bar secured at its upper end in the out-turned portion 79 and pivotally secured at its 95 lower end between the inner ends of the double cross arm 74 of the gathering fork 73. The cupped member 39, hereinbefore referred to, is provided with a recessed portion 81 formed in the lower face of the cup 100 and provided with a vertical wall 82 and an inclined wall 83. 84 indicates a tripping pin carried by the sleeve member 58 and extending at its upper end between the spokes of the revoluble member 36 and bearing against the lower face of the cup member 39. 85 indicates a lever swung upon the upper end of the axle 35 and fitting within the recess 38. The outer end of the lever 85 projects outwardly beyond the circumference of the revoluble member 36. 86 indicates a bracket inverted U-shape in form and secured to the lower face of the lever 85 between the inner periphery of the gear portion 37 and the outer periphery 110 of the annular flange 40 of the cup member 39. 87 indicates a spring plunger held in the bracket 86 and provided with a headed end 88 held in engagement with the ratchet teeth 41 formed in the flange 40. 89 indicates a link rod which extends from the outer end of the lever 85 to a suitable operating lever (not shown) located in proximity to the driver's seat. 90 indicates a spring pressed locking dog pivotally carried by the radial extension 22 of the plate 21 in engagement with the ratchet teeth 41. By this means the rotation of the cup member 39 in the direction of arrow (see Fig. 4) 120 is prevented. A cord 91 extends from each 125 130

of the bars 78 to the side of the corresponding pocket of the receiver 43.

It will be noticed that the weight of the arms 68 and co-acting mechanism serve to hold the pin 84 in close contact with the lower face of the cupped member 39. 92 indicates a cam piece carried by the extension 28^x of the portion 23 in close proximity to the outer periphery of the geared portion 37 and in the path of the upwardly extending inclined portions of the tail pieces 66. 100 is a compressor member. The member 100 is attached at one end to the tubular bearing 16 and extends around in the form of a semi-circle to the point 100^x and bears against the horizontal portions of the arms 68 so as to hold them down and the sheaves vertical. As the machine is traveling in the direction of arrow (see Fig. 1) it is essential that the sheaves at the back portion of the device drop vertically on to the ground otherwise such sheaves would be overthrown by the forward travel of the machine. The forward travel of the machine carries the heads of these rear sheaves forward inclining these sheaves toward the center of the shock. The sheaves dropped at the front portion of the device are not held by the compressor bar and, therefore, the corresponding arms 68 tend to swing out and drop these sheaves in an inclined position against the rear sheaves.

Having described the principal parts involved in my invention I will briefly describe the operation of the same.

The sheaves are delivered and tied on the binder deck in the usual manner against the compressor arm 2. The delivery arms 5 and 6 are carried around to deliver the sheaf. The cams 10 and 11 which, as hereinbefore described, gradually increase in radius in the direction of travel of the delivery arms 5 and 6, serve to give a forward throw to the delivery arms 5 and 6 as they travel radially around and therefore when they come into contact with the sheaf tend to throw the sheaf more quickly upward. The cam 11 is slightly larger than the cam 10 and, therefore, the arm 6 leaves the cam 10 before the arm 5 leaves the cam 11. The arm 5, therefore, gives the sheaf a greater throw than the arm 6 so as to carry the sheaf into a vertical position. The shaft 27 is continuously driven from the knotter shaft as long as the knotter shaft rotates by means of the gears 31 and 32, shaft 29 and pinions 33 and 28. By this means the pinion 34 and gear 37 of the revoluble member 36 is driven from the knotter shaft so as to rotate such member in the direction of arrow (see Fig. 1). By this means the tail pieces 66 are successively carried into engagement with the cam piece 92. The cam piece 92 depresses the tail piece 66 as it is brought into contact therewith so as to

swing the arm 68 outwardly into the position shown at "a" in Fig. 1 of the drawings.

As above described the delivery arms 5 and 6 throw the sheaf upward into a vertical position, the upper portion of the sheaf 70 coming in contact with the cord 91 when the cord is in the position shown at "a." When the sheaf is thrown into this position the tail piece 66 is carried free of the cam piece 92 so that the arm 68 is freed. Simultaneously with this operation the sheaf strikes the cord 91 exerting an inward pull on the arm 68 assisting in drawing the fork 73 into the sheaf as the arm 68 falls downward and inward by gravity. The arm 68 then drops to a vertical position carrying the sheaf into the corresponding pocket 49. Each pocket 49, 50, 51, 52, 53 and 54 receives its sheaf in this manner. The vertical pin 84 is also carried around with the revoluble member, sleeve 58 and sheaf receiver 43 (in the direction of arrow see Fig. 1). When all the pockets of the sheaf receiver have been filled the pin is brought opposite the recessed portion 81. By this means the forks 73 are freed so that the weight of the sheaves throws the forks downwardly toward a vertical position, the lever 75 being tilted on its pivot and the sleeve 58 being carried upwardly on the axle 35 and the upper end of the pin 84 carried into the recessed portion 81. When the sheaves are freed as above described they drop downward from the sheaf receiver on to the ground forming a circular shock. Immediately this operation is completed the upper end of the pin 84 travels up the inclined wall 83 of the recess 81 thereby carrying the forks 73 back to their normal or sheaf engaging position. This operation is repeated all around the field. At the end of the cut it may be that the number of sheaves gathered by the shocker is not sufficient to form a complete shock and therefore will not automatically drop the sheaves before a new cut is started. In order to accomplish this the driver of the binder operates the lever 85 so as to turn the cupped member 39 by means of the spring plunger 88 and ratchet 44 in the opposite direction of arrow indicated in Fig. 4 thereby turning the cupped member back so that the recess is again brought opposite the pin 84 by successive operations of the lever 85 so as to drop the number of sheaves held in the receiver. A new cut of grain may then be started so that the shocks formed and deposited will be in alinement with the shock formed from the previous cut.

From this description it will be seen that I have devised a very simple construction of machine which will be light and durable and which will not only automatically gather the sheaves into a complete shock and deposit the shock when complete upon

the ground in a vertical position but will also when the machine comes to the end of a cut deposit any number of sheaves which may be gathered by the machine and which 5 will not form a complete shock before a new cut in the grain is started and thus will insure the shocks being set up evenly in the field and therefore more easily gathered when required.

10 I am aware that cams have been used before for operating the delivery arms for ejecting the sheaf from the binder deck. It has been found, however, that these cams do not throw the sheaf with sufficient quick- 15 ness to insure that the forks 73 engage therewith when the arm 68 is freed from the cam 92. In order to overcome this defect I have formed the cams with a gradually increasing radius which gives a quicker throw 20 to the delivery arm as it revolves around to the delivery position against the sheaf so as to carry the sheaf quickly into the path of the fork 73 simultaneously with the freeing of the arm 68 and commencement of 25 its fall inward toward the receiving pockets.

What I claim as my invention is:

1. In a device of the class described, the combination with the vertical supporting axle, of a sheaf receiver rotatably mounted 30 thereon and comprising a plurality of fabric strips connected together along their longitudinal center to form radially extending connected flaps and stiffening means for holding the outer edges of the flaps radially 35 outward to form a series of pockets.

2. In a shocker attachment for binders, the combination with the supporting member carried by the binder, of a vertical axle depending from such supporting member, a 40 revolute member carried by the axle, means for driving the revolute member from the binder, a shock receiver carried by the vertical axle and rotatable with the revolute member and comprising a series of 45 open ended vertical pockets arranged radially around the center of the axle, a sheaf gathering mechanism movable in a radial direction independent of the pocket and comprising a swinging arm carried by the 50 revolute member radially opposite the center of each pocket, releasable means at the lower end of each arm for engaging the sheaf, and a cord connection extending normally in downwardly looped form between 55 one wall of the corresponding pocket and the gathering mechanism.

3. In a shocker attachment for binders, the combination with the supporting member carried by the binder, of a vertical axle 60 depending from such supporting member, a revolute member carried by the axle, means for driving the revolute member from the binder, sheaf gathering mechanism comprising a series of arms pivoted to the revolute 65 member and extending radially therefrom,

70 a pivoted fork swung at the lower end of each arm, a tripping member carried by the axle, mechanism interposed between the tripping member and each fork and for holding each fork in the sheaf engaging position and for simultaneously releasing all the forks at the tripping point, and manual means for turning the tripping member so as to drop the forks at any point in the revolution of the revolute member. 75

4. In a shocker attachment for binders, the combination with the supporting member carried by the binder, of a vertical axle depending from such supporting member, a revolute member carried by the axle, means 80 for driving the revolute member from the binder, a shock receiver carried by the vertical axle and rotatable with the revolute member and comprising a series of open ended vertical pockets arranged radially 85 around the center of the axle, a series of sheaf gathering arms pivotally connected to the revolute member and extending radially therefrom, a fork pivoted to the lower end of each arm, a lever and a link mechanism carried by the arm for raising and lowering the forks, a member rotatably carried on the axle provided with a tripping recess, a sleeve carried by the axle and having radial arms, links engaging the 90 radial arms with the inner ends of the levers, and a pin extending upwardly from such sleeve against the face of the rotatable member in the path of the tripping recess. 95

5. In a shocker of the class described, the combination with the vertical supporting axle, the tripping member rotatably held thereon, a tripping pin co-acting with the tripping member and a series of forks and fork operating mechanism connected to the 100 tripping pin and carried so as to rotate around the axle and be simultaneously released by the tripping member and co-acting tripping pin, of means for manually turning the tripping member to trip the fork operating mechanism at any point during 105 their rotary movement. 110

6. In a shocker of the class described, the combination with the vertical supporting axle, the tripping member rotatably held thereon, a tripping pin co-acting with the tripping member and a series of forks and fork operating mechanism connected to the 115 tripping pin and carried so as to rotate around the axle and be simultaneously released by the tripping member and co-acting tripping pin, means for preventing the rotation of the tripping member in the direction of travel of the tripping pin in contact therewith and yet allowing free movement 120 of the tripping member in the opposite direction, of manual means for turning the tripping member in the reverse direction to the direction of travel of the tripping pin. 125

7. In a shocker of the class described, the 130

combination with the vertical supporting axle, the tripping member rotatably held thereon and provided with a series of ratchet teeth arranged around its periphery, 5 a tripping pin co-acting with the tripping member, and a series of forks and fork operating mechanism connected to the tripping pin and carried so as to rotate around the axle and be simultaneously released by the 10 tripping member and co-acting tripping pin, of a manually operated lever swung upon the axle, a spring plunger carried thereby in contact with the ratchet teeth of the tripping member and a spring dog in engagement with the ratchet teeth designed to prevent rotary movement of the tripping mem- 15

ber in the direction of travel of the tripping pin.

8. In a shocker attachment for binders, the combination with a vertical axle, sheaf 20 receiving pockets supported by and turnable around the axle, and pivoted inverted L-shaped fork arms also carried by the axle and rotating with the pockets, of a stationary arc-shaped bar extending over the horizontally extending portion of the rearwardly extending arms of the device to prevent their upward swing. 25
